UNITED STATES PATENT OFFICE.

ESTEL L. CROWHITE, OF KANSAS CITY, MISSOURI.

PORTABLE WIRE-WEAVING MACHINE.

Application filed September 23, 1921. Serial No. 502,630.

To all whom it may concern:

Be it known that I, ESTEL L. CROWHITE, a citizen of the United States, residing at Kansas City, in the county of Jackson and State of Missouri, have invented certain new and useful Improvements in Portable Wire-Weaving Machines, of which the following is a specification.

My invention contemplates certain new and useful improvements in wire fence machines, and one object is to provide a light and simple machine of this character which can be manufactured cheaply and is portable, so that it can be easily and quickly moved along a line of stretched fence wires for the purpose of weaving in the vertical stay wires.

The invention will be hereinafter fully set forth, and particularly pointed out in the claims, and in order that said invention may be fully understood, reference will now be had to the accompanying drawings, in which:

Fig. 1 is a side elevation of the machine.

Fig. 2 is a front elevation of the machine.

Fig. 3 is a detail perspective view of the rotary weaver body.

Fig. 4 is an enlarged fragmentary section on line IV of Fig. 2.

Fig. 5 is a broken plan view of a guide member.

Fig. 6 is a broken detail of a portion of a wire fence with several stay wires woven thereon.

In the drawings, like characters of reference indicate corresponding parts throughout the different views.

In carrying out the invention, I employ a frame 1 consisting of a bracket 2, and a yoke 4 which latter is removably secured to the former by suitable means such as bolts 6, in order that the rotary weaver body 8 may be placed in position in the frame 1. The bracket 2 is provided at its upper and lower ends with guide members 10, which are slidably mounted upon a bar 12 provided at its lower end with a spike 14 adapted to be forced into the ground, to steady the machine while in operation. The spike 14 is aided in steadyng the machine by a hook 15 slidable on the bar 12 so that said hook 15 may be successively engaged over the strand wires B, as the stay wires A, are fastened thereto.

The weaver body 8 is of tubular form and provided at its ends with journals 16, which

are mounted in bearings 18 and 20 formed integral with the bracket 2 and the yoke 4, respectively. A gear wheel 22 is cast or otherwise fixed to the weaver body 8 adjacent to one of the journals 16, while the opposite journal is provided with a longitudinally-projecting member 24 provided at its end with a hook 26 for forming a knot in the vertical stay wire A and twisting the same about the longitudinal strand wires B of the fence. A longitudinal slot 28 extends from end to end of the weaver body 8 and through the gear wheel 22 to admit the strand wires B of the fence to the relatively large bore extending longitudinally through said weaver body 8. An opening 30 communicates with the slot 28 intermediate its ends for the admission of barbs should the same be present on the longitudinal strand wires B.

The weaver body 8 is adapted to be rotated step by step in securing the stay wires A to the strand wires B through the intermediacy of a handle 32 and a detent 34, which latter is yieldably held in engagement with the gear wheel 22 by a coil spring 36. The handle 32 is cast integral with a fork 38 terminating at its ends in segmental members 40, loosely mounted upon the journals 16 beside the bearings 18 and 20 and abutting shoulders 42 at the inner ends of said journals 16 for preventing longitudinal movement of the weaver body 8 in the bearings 18 and 20.

In order that the fork 38 may be readily placed in position upon the weaver body 8, said yoke is made in two parts removably connected by bolts 44, as disclosed by Fig. 2. The bearings 18 and 20 have slots 46 and the fork 38 has slots 48. The slots 48 and 28 are brought into coincidence with the slots 46 to enable the machine to be placed in position or removed from a strand wire of the fence.

The detent 34 is beveled at one end as indicated at 49 and provided at its opposite end with a knob 50 whereby it may be raised and rotated a half revolution when the rotary movement of the weaver body 8 is to be reversed. The detent 34 is held in either of its positions by lugs 52 cast thereon and which are yieldably held in recesses 54 in the fork 38, by the pressure of the spring 36.

Having thus described the construction of the invention, I shall now briefly describe its operation and utility. Starting at the

top, the machine is placed in position over the uppermost strand wire B of the fence where it is steadied by the bar 12, the spike 14 of which is forced into the ground and 5 the hook 15 of which is engaged over said strand wire. Both hands of the operator are now free to manipulate the stay wire and the handle 32. The upper end of the stay wire is engaged with the notched portion 10 25 of the member 24 and then twisted around the upper strand wire by rotating the weaver body 8 step by step through the intermediacy of the gear wheel 22, the handle 32 and the detent 34. After the upper 15 end of the stay wire is thus fastened to the upper strand wire the hook 15 and the machine are removed from said upper strand wire and slid downwardly upon the bar 12 to the next strand wire over which they 20 are engaged in the same manner as above described. The stay wire is then held in engagement with the hook or knotter 26 which is rotated through the manipulation 25 of the handle 32 as above described, causing said knotter to twist the stay wire around the strand wire. On completion of the last-mentioned operation the hook or knotter 26 extends through a loop or knot C formed in the stay wire and is removed 30 from said loop or knot by reversing the direction of the weaver body 8, which can be readily accomplished after reversing the position of the detent 34. The stay wire is then successively fastened in the same manner 35 to the remaining intermediate strand wires, after which its lowermost end is twisted about the lowermost strand wire in the same manner as its upper end was twisted around the upper strand wire. The 40 stay wires A may be placed as closely together as desired.

From the foregoing description it is apparent that I have provided a weaving machine possessing the advantages above pointed out, and while I have shown and described the preferred construction, combination and arrangement of parts, I reserve the right to make such changes as properly fall within the spirit and scope of the invention.

Having thus described my invention,

what I claim and desire to secure by Letters Patent, is:

1. In a machine of the character described, a weaver body having a relatively large core extending longitudinally therethrough and a longitudinal slot communicating with said bore to admit thereto strand wires, said slot having a large opening to admit barbs on said wires, an element on said weaver body for twisting stay wires onto the strand wires, a frame having slots to admit the strand wires and in which the weaver body is journaled, and means for rotating the weaver body. 55 60 65

2. In a wire fence machine, a weaver body having a longitudinal slot extending therethrough to receive strand wires, an element projecting from one end of said weaver body for twisting stay wires onto the strand wires, a gear wheel fixed to the weaver body and having a slot communicating with the longitudinal slot in the weaver body, a reversible detent to rotate said gear wheel in reverse directions, a handle to actuate said detent, a frame having slots to admit the strand wires and in which the weaver body is mounted, and a support for said frame. 70 75

3. In a wire fence machine, a weaver body having a longitudinal slot extending therethrough to receive strand wires, an element on said weaver body for twisting stay wires onto the strand wires, a gear wheel fixed to said weaver body, a fork 80 85 rockably mounted upon the weaver body, a detent reversibly mounted in said fork and adapted to rotate the gear wheel in opposite directions, a spring yieldably holding said detent in engagement with the gear wheel, means on the detent and the fork to prevent accidental reversal of said detent, a handle to the fork, and a frame having slots to admit the strand wire and in which the weaver body is journaled. 90 95

In testimony whereof I affix my signature, in the presence of two witnesses.

ESTEL L. CROSWHITE.
